UNITED STATES PATENT OFFICE

JOHN PENROD AND ROBERT D. THOMPSON, OF OKMULGEE, OKLAHOMA.

OIL WELL.

Original application filed November 10, 1920, Serial No. 423,082. Divided and this application filed August 25, 1921. Serial No. 495,367.

To all whom it may concern:

Be it known that we, JOHN PENROD and ROBERT D. THOMPSON, citizens of the United States, residing at Okmulgee, in the county of Okmulgee and State of Oklahoma, have invented a new and useful Oil Well, of which the following is a specification.

This invention relates to oil well apparatus, the same being a divisional application 10 of the application filed by us under date of November 10, 1920, and which bears Serial Number 423,082.

The primary object of the invention is to provide novel means for creating a vacuum 15 at the base of the well to cause the natural gases and water to be carried off with the passage of oil through the pump tubing.

Another object of the invention is to provide a casing having a bell-shaped lower extremity, the casing being in communication 20 with the well tubing so that fluid passing through the casing may enter the well tubing.

With the foregoing and other objects in view which will appear as the description 25 proceeds, the invention resides in the combination and arrangement of parts and in the details of construction hereinafter described and claimed, it being understood that changes in the precise embodiment of the invention herein disclosed, may be made within 30 the scope of what is claimed, without departing from the spirit of the invention.

Referring to the drawing:—

Figure 1 is a sectional view through the 35 lower portion of the well apparatus.

Figure 2 is a sectional view through the upper portion of the well apparatus.

Figure 3 is a sectional view taken on line 3—3 of Fig. 1.

40 Referring to the drawing in detail, the apparatus comprises an upper casing 5 and a lower casing 6, the casings being connected by means of the threaded bushing 7, the lower portion of the bushing 7 being reduced 45 to accommodate the lower casing 6 which is of a less diameter than the diameter of the upper casing 5.

The lower casing 6 is provided with a bell-shaped extremity 8 through which the oil,

passing through the well apparatus, is 50 drawn. Supported by the bushing 7 and disposed within the lower casing is a tube 9 that is arranged in spaced relation with the lower casing to provide a passageway therebetween, the tube 9 being provided with 55 openings 10 to permit the fluid entering the passageway to move to the interior thereof.

This tube is relatively long and provided with a threaded lower extremity to accommodate the securing collar 11 which is positioned on the upper extremity of the intake pipe 12 to secure the intake pipe 12 to the tube 9.

Supported within the tube 9 and secured in position by means of the collar 13, is a tube 65 14 which has its upper end disposed within the bushing 7 and arranged in spaced relation with the tube 9, there being provided a clearance at the upper end of the tube to permit fluid passing into the space between 70 the tube and the tube 9 to enter the valve chamber 15. This valve chamber 15 receives fluid from the lower section of the apparatus and delivers the same to the upper section, the ball valve member 16 being provided to 75 control the passage of fluid from the lower section to the upper section.

This ball valve moves within the valve cage 17, at the lower end of which is provided the valve seat 18 on which the ball 80 valve 16 seats to prevent fluid moving in the upper section of the apparatus, from falling back into the lower section.

It might be further stated that a one-way valve member indicated at 19 controls the 85 passage of fluid through the intake pipe 12 and the tube 14, so that fluid drawn into the upper portion of the tube will not flow into the well on the reverse movement of the pump supported at the upper portion 90 of the well apparatus, and which is not shown in the present writing.

Having thus described the invention, what is claimed as new is:—

In a device of the character described, an 95 upper casing and a lower casing, a working barrel disposed within the upper casing, a tube disposed within the lower casing, a

tube disposed within the first mentioned tube and arranged in spaced relation therewith to provide a sand pocket, a plunger adapted to draw fluid through the lower casing, and 5 a bushing for connecting the upper and lower casings.

In testimony that we claim the foregoing

as our own, we have hereto affixed our signatures in the presence of two witnesses.

JOHN PENROD.
ROBERT D. THOMPSON.
